UNITED STATES PATENT OFFICE.

ARCHIE EDGAR LOW, OF OTTAWA, ONTARIO, CANADA.

SEALING MEANS.

Application filed March 22, 1927. Serial No. 177,419.

This invention relates to improvements in sealing means and more particularly to sealing means adapted to be used in connection with locks and especially with that 5 class of lock with which is associated a protruding locking bolt, such as grommet locks for mail bags and the like.

Generally speaking the present invention may be described as an improved locking 10 seal for mail bag locks as covered in my pending United States application Serial No. 162,771, filed January 22nd, 1927.

The objects of the invention are to provide, in connection with my grommet lock, 15 improved means for sealing said lock, which cannot be tampered with without breaking and which, in operation, will double lock the seal-carrying strip.

Other objects of the invention are to provide a seal of this description that can be 20 used alone or with locks of other construction than grommet and adapted to other purposes. In short, a locking seal in the form of an attachment that can be employed 25 under any suitable circumstances.

A further object is to provide a device that when locked cannot be interfered with in any way without the interference being disclosed.

In the art to which the present invention 30 relates it has heretofore been proposed to seal a locking bolt with a strip extending therethrough and provided at its loose ends with a seal. This, as will be readily appreciated, was by no means a reliable guard 35 against tampering and it was practically impossible to know whether attempts had been made to do so or not.

In accordance with the present invention 40 these difficulties are practically overcome and a combined "safety first" seal is provided which cannot be tampered with with impunity.

This result is largely due to the fact that 45 the sealing means and the lock are intimately associated with one another, a sealing strip of special and novel construction being detachably anchored in the locking bolt and extending through openings registering with one another at separate points 50 in the lock casing or cover to engage with a locking member of special construction con-

necting said openings and rigidly secured within the lock casing whereby tension in either direction on the sealing strip will 55 automatically cause it to break.

A feature of the present construction is its simplicity combined with durability and efficiency in operation.

Furthermore, the addition of the seal and 60 the means for automatically locking it necessitating practically no material changes in the existing construction of mail bag and other locks, enable it to be readily included therewith.

Another essential feature of my invention over the art as heretofore practised is that with it the seal-carrying strip is doubly locked, this being provided for by the improved construction of the sealing strip itself and the locking member mounted under cover and through which the sealing strip travels.

From a commercial standpoint and generally speaking, the results obtained at comparatively low cost, in security for the contents of mail bags and the like, are very considerable.

Reference is now had to the accompanying drawings, in which a preferred example 75 of the invention is disclosed as applied to the mail bag lock of the grommet type described in the above mentioned United States application and in which like numerals of reference indicate corresponding parts in each figure,

Figure 1 is perspective view of the combined lock and seal.

Figure 2 is a side elevation, partly in section.

Figure 3 is a perspective view of the locking bolt.

Figure 4 is a perspective detail of the bracket with a passageway for the strip secured within the lock casing or cover.

Figure 5 is a plan view of same.

Figure 6 is a section on the line 6-6 of Figure 5.

Figure 7 is a perspective view of a modified form of bracket with a passageway for 100 the sealing strip.

Figure 8 is a sectional detail of same.

Figure 9 is a longitudinal section of the strip.

Figure 10 is a perspective view of the locking plate.

Figure 11 is a longitudinal section of a modified form of strip.

Referring now more particularly to the drawings, A designates a mail bag lock of well known grommet lock construction and B the locking bolt extending therethrough and protruding beyond the casing, as at 10. C is the neck strap for the mail bag, to which the opposite end of the locking bolt B is rigidly secured.

The protruding end of the locking bolt is provided with a slot 11 to engage with a flexible metallic strip 12 formed with a seal 13 to retain the strip within the locking bolt slot 11, in other words, to detachably anchor the strip in the protruding end of the locking bolt.

Adjacent to this protruding end is an opening 14 in the top 15 of the cover or casing of the lock, while registering with this opening is a second opening 17 in the side 18 of the casing.

Rigidly mounted in the side of the casing between the openings 14 and 17 is the strip locking member D (see Figure 4) forming an essential feature of my invention and comprising a scoop-shaped channelled body portion 19 having integral therewith a plate 20 conforming to the contour thereof and adapted to be rigidly secured on the inside of the casing (see Figure 2), the curved base of the body portion being designed to register at opposite ends with the openings 14 and 17 and to form therebetween a downwardly curved guideway 22.

Within the scoop-shaped channelled body portion is fitted a curved plate 23 of resilient metal, folded upon itself and the over-hanging ends being adapted to engage with the slots 24 in the sides 25 and 26 of the body portion 19, the over-hanging ends of plate 23 protruding beyond said sides (see Figure 4).

Centrally arranged in the top is a slot 27 adapted, when in position, to register with the top opening 14 in the casing, designed to engage, as hereinafter more fully described, with the metallic sealing strip 12.

As illustrated in Figure 9, this strip is formed with spaced bosses 28 alternately provided on opposite sides thereof and protruding in the same direction to engage and lock with the locking member at the bottom and top thereof.

In Figure 11 a boss 29, spaced from the aforementioned bosses 28, is shown protruding in the opposite direction to engage with the slot in the top of the locking plate.

From the foregoing it will be seen that the plate 23 of spring or resilient material, folded upon itself, will tend to clamp against the base of the portion 19 and similarly when the sealing strip is introduced through

the opening 14 and through the slot 27 and downwardly between the folds of the locking plate 23, as it may be called, and then outwardly through the opening 17, it can be drawn in this direction through the formation of the bosses 28 until the boss 29, protruding in the opposite direction to the bosses 28, engages with the plate 23.

Furthermore, any interference with the strip after it has passed through the member D and between the opening 14 and the locking bolt will cause one of the bosses 28 to engage with the lower end of the locking plate 23 while at the same time the boss spaced therefrom on the other side will automatically engage and lock with the slot 27 in the top of the plate.

In this way it will be seen that the seal-carrying strip is doubly locked against tampering or pulling back once it has been inserted and drawn through the member D. This is a feature of my invention, which, it is submitted, has not heretofore been described or disclosed and the advantages of it over sealing means at present in use will be self-evident.

The combination with the member D, which is maintained under cover in the casing, providing a locking element in one direction for a seal-carrying strip in turn provided with bosses in spaced relationship to one another and alternately arranged on different sides of the strip, ensures the maximum of protection in the securing of mail bags or any other property to which it can be applied.

In the modified form, as illustrated in Figure 7, of the locking member D, the spring locking plate, instead of being folded on itself and having an extended top with a slot in it, is shown as a single plate 30, the over-hanging ends of which are adapted to engage with the slots in the sides of the scoop-shaped channelled body portion and designed, as already described, to engage with the bosses 28 on the strip when the latter is drawn backwardly. This construction only provides for a single locking of the strip whereas, as previously mentioned, the locking member provides for double locking thereof.

It may here be mentioned that the spaces between the bosses 28 on opposite sides of the strip are arranged to correspond with the spaces between the lower end of the locking plate and the slot 27 in the top of the plate 23, so that, as hereinbefore described, two of the bosses simultaneously and automatically engage with the locking plate.

As many changes could be made in the above construction, and many apparently widely different embodiments of my invention, within the scope of the claims, constructed without departing from the spirit or scope thereof, it is intended that all mat-

ter contained in the accompanying specification and drawings shall be interpreted as illustrative and not in a limiting sense.

What I claim as my invention is:—

5. 1. A device of the character described comprising in combination, a casing, a locking bolt extending through and protruding beyond the casing and provided with an opening therethrough, openings in the casing, a locking member rigidly mounted within the casing between said openings and communicating therewith, spring locking means in said member, a strip of flexible metal formed with a seal adapted to engage 10 with the opening in the bolt and to extend through the openings in the casing and through the locking member within the casing, and to travel freely in one direction, means formed on said strip adapted at a predetermined point in the travel thereof to engage with the locking member to lock the strip and means further formed on said strip adapted on the strip being tensioned in the opposite direction to engage with the locking member at two different points simultaneously to double lock the strip. 15
2. Sealing means for mail bag locks comprising in combination a casing, a locking bolt, a substantially channel-shaped member, 20 a plate of resilient metal folded on itself adapted to fit into the channel-shaped member, a slot in the folded end of said plate and extensions integral with the folded end, slots in the sides of the channel-shaped member to engage with said plate, a sealing strip formed at spaced intervals on opposite sides thereof with bosses protruding in the same direction whereby on the strip being inserted in the channel-shaped member it will travel 25 freely in one direction through the slotted head and through the plate and whereby on the strip being tensioned in the opposite direction a boss on one side thereof will engage with the lower end of said plate and a boss on the opposite side will engage with the slot in said plate to securely double lock the strip. 30
3. A sealing attachment for locks comprising a channel member open at both ends, 35 a plate of resilient metal folded on itself provided with a slot and designed to fit snugly into said channel and to automatically impinge on the bottom thereof, a sealing strip adapted to travel freely in one direction and up to a predetermined point through said plate and the channel member, similarly protruding bulges formed in the strip spaced from one another and alternately arranged on opposite sides of the strip whereby on tension being exerted on the strip to move it backwardly the strip automatically engages with said plate at separated points to double lock therewith. 40
4. A sealing attachment for locks comprising a channel member open at both ends, a
- plate of resilient material folded on itself and provided with a slot designed to fit snugly in said member, a metallic seal carrying strip operatively engaging with said plate, stops spaced from one another and 70 arranged alternately on the strip, a stop spaced from the aforementioned stops whereby on tension being exerted on the strip to move it in one direction the stops on the strip will simultaneously and automatically engage with the plate to double lock with the strip and whereby on the strip being tensioned in the opposite direction the stop will automatically engage and lock with said plate. 75
5. A sealing attachment for locks comprising a channel member provided with a spring plate folded on itself and having a slot in the folded end, slots in the sides of the channel member, means integral with the slotted end of the plate for engaging with said slots, a seal carrying metallic strip adapted to travel freely in one direction through the locking member and means on the strip adapted at a predetermined point 80 in its travel through the locking member to lock the strip and means further formed on the locking member adapted on the strip being tensioned in the opposite direction to automatically engage with and double lock 85 the strip in said member. 90
6. A sealing attachment for locks comprising a channel member provided with a spring plate folded on itself and having engaging means therein, means in the sides of the channel member and means integral with the plate for engaging with said means, a seal carrying strip of flexible material adapted to travel freely in one direction through the locking member, and means 100 formed on the strip adapted on the strip being tensioned to automatically engage at one or more points in the channel member to lock the strip therein. 105
7. A sealing device of the character described comprising a strip engaging member adapted to form a guideway, an intercepting spring plate rigidly mounted in the guideway and automatically impinging against the bottom thereof, a seal carrying strip 110 formed with a plurality of suitably arranged and spaced bulges adapted to travel in the guideway freely in one direction to a predetermined point and on being tensioned to travel in the opposite direction to automatically lock with said plate, a casing for the strip receiving member having an intake and discharge opening therein communicating with said member. 115
8. The combination with a lock having a 120 protruding locking bolt, a seal carrying strip in said bolt, a lock casing, a locking member rigidly mounted within the casing, strip intake and discharge openings in the casing communicating with said member and a 125
- 130

spring plate in said member adapted to permit free travel of the strip through the locking member in one direction and to automatically lock the strip in its travel through said member in the opposite direction.

9. The combination with a lock having a protruding locking bolt, a seal carrying strip in said bolt, a lock casing, a locking member rigidly mounted within the casing, strip intake and discharge openings in the casing

communicating with said member and a spring plate in said member adapted to permit free travel of the strip up to a predetermined point in one direction and to automatically lock the strip in its travel through said member in the opposite direction. 15

In witness whereof I have hereunto set my hand.

ARCHIE EDGAR LOW.
